PORTABLE LAMP

Filed Oct. 26, 1922

INVENTOR
FRANK H. BUSSMANN,
by Roy M. Eilers ATTORNEY.

UNITED STATES PATENT OFFICE.

FRANK H. BUSSMANN, OF ST. LOUIS, MISSOURI, ASSIGNOR TO BUSSMANN MANUFACTURING COMPANY, OF ST. LOUIS, MISSOURI, A CORPORATION OF MISSOURI.

DESIGN FOR A PORTABLE LAMP.

Application filed October 26, 1922. Serial No. 4,098. Term of patent 14 years.

To all whom it may concern:

Be it known that I, FRANK H. BUSSMANN, a citizen of the United States, residing at St. Louis, in the State of Missouri, have invented a new, original, and ornamental Design for a Portable Lamp, of which the following is a specification, reference being had to the accompanying drawing, forming part thereof.

The figure is a side view of a portable lamp showing my new design.

I claim:

The ornamental design for a portable lamp, as shown.

FRANK H. BUSSMANN.
